MULTIPLYING MACHINE

Torkel E. Torkelson, Merrick, N. Y., assignor, by
mesne assignments, to International Business
Machines Corporation, New York, N. Y., a cor-
poration of New York

Application December 20, 1932, Serial No. 648,036

1 Claim. (Cl. 235—61)

This invention relates to improvements in calculating machines and, more particularly, the invention is directed to improvements in multiplying machines.

5 One of the objects of the present invention is to provide a multiplying machine which is capable of effecting computations at a very rapid rate.

A further object of the invention is to provide an improved multiplying machine adapted to effect 10 multiplications of factors involving multi-denominational amounts by utilizing timed impulses derived from multiplying commutators.

At the present time it is the common practice in multiplying machines to multiply each denominational order of the multiplicand by one of the digits of the multiplier and the results (i. e., the partial products) are separately assembled until the multiplicand has been separately multiplied by each of the digits of the multiplier. Following this, the partial products are assembled to form the complete product of the multiplicand and multiplier. The operation of multiplication according to this plan necessitates separate accumulating or storing devices to separately assemble the different partial products and further mechanism for assembling the partial products to complete the problem. According to the present invention, it is proposed to provide a single accumulator or storing device into which all of the partial products may be entered, thus providing a simpler and more compact machine and eliminating the mechanism necessary for the final assembling of the partial products.

The machine proceeds in operation by establishing a progression correlated to one of the factors and constituting all of the results which can come from that factor taken with any other possible digits in the notation and in the remaining factor. Thus, if 8 were the multiplier, the machine would form a progression as follows: 8—16—24—32—40—48—56—64—72. These amounts, it will be noted, are an arithmetical progression based upon 8 and in their entirety constitute all the results which might be obtained by multiplying any of the digits of the tens notation by 8.

Having established such progression wherein the denominational values of the terms are still undetermined, a selection is made from the terms of this progression. It is to be further noted that 50 only one such progression will be formed regardless of the size of the multiplicand. The multiplicand entry then acts to select out of the already established progression a term or number of terms or perhaps all or none of them according to the 55 amount of the multiplicand.

Considering the example $6764 \times 8 = 54112$ by way of illustration, the following terms of the 8 progression will be selected: 32—48 and 56. These selected terms are the ones representative of multiplying 4 and 8, 6 and 8, and 7 and 8.

In the above computation, the multiplication of 6 and 8 occurs twice. Accordingly, the multiplicand makes a selection of the 48 term from the progression and uses it twice and in doing this, so effects an allocation of the denominational order values of 48 to properly enter such values into the receiving device. One of the 48's has a value allocated to it of 48000 and the other a value of 480. Up to the point where the 48 was selected by the multiplicand it had an abstract value of 48 and no denominational value whatever. The multiplicand similarly allocates values to the other selected terms. Thus, 56 has an allocated denominational value of 5600 and 32 remains as 32. These terms are now assembled in the receiving device thus:

32	
480	
5600	
48000	
54112	25

The machine, furthermore, in creating and co-ordinating the progression, proceeds by first potentially creating all of the digit values of a notation or representations thereof wholly without regard to their denominational order or arrangement with respect to any problem that the machine is to compute. Thus, with the computations involving a tens system of notation, the machine will create transient representations of the different digits 1 to 9. It is these transient representations that the machine coordinates into a progression in accordance with one of the factors. 30 35 40

The multiplicand device in selecting and allocating denominational values acts so that the transmission of the various representations from the progression into the receiving device takes place concurrently. In this way, operating time is saved. 45

Summarizing briefly, the machine starts with a transient representation of digits, coordinates them into a transient progression, and selects and allocates from said progression. The result is obtained only after the completion of the computing cycle and upon the transfer of the representation into the receiving device. The ultimate results are made potentially available and are developed by the computing cycle by coordination, the selec- 50
55

tion and denominational allocation to be interpretable upon their entry into the receiving device. By virtue of this novel law of operation, the machine is relatively simple in construction and expeditiously handles complex problems.

A further object of the invention resides in the provision of a machine which will effect such computations more rapidly than heretofore.

10 A further object resides in the provision of a machine which will effect such a class of computations with simpler mechanism than has been known heretofore.

A further object of the present invention resides in the provision of a novel impulse emitting and coordinating means whereby single emitting devices may be used for emitting the impulses which are to ultimately designate product amounts when received by the receiving device, which impulses are wholly uncoordinated to denominational orders, and to further provide for the denominational coordination of such impulses as they pass to the receiving device.

25 Before describing the detailed construction and operation of the machine, it may be stated that use is made of a single register for receiving and accumulating all the partial products of the machine as they are computed and will therefore indicate the complete product upon completion of the last computing operation.

30 The register employs differential gearing which as here shown, is adapted to be controlled by differentially timed impulses. The impulse emitting means are timed and coordinated to the cycle of the register, such impulse emitting means being driven concurrently and synchronously with the register. The factor entry means are intended to control the flow of impulses from the emitters to the receiving means or register.

35

According to the preferred form of the invention, a separate impulse emitting means is provided for partial products known as left hand partial products and another for the so-called right hand partial products. The emitters are arranged to operate in succession to first enter the left hand partial products derived from the multiplication of the first digit in the multiplier by the multiplicand into the register and then to enter the right hand partial product of such multiplication into the same register. Following this, the left and right hand partial products of the remaining orders of the multiplier are successively entered into the register. The register itself is provided with novel transfer mechanism which, by virtue of the differential construction of the register, will effect transfer operations during that portion of the cycle in which entries are being effected. This permits the construction of a register having an operating cycle not longer than the period required to enter items therein from the emitters. This in turn permits shorter operating cycles than has heretofore been possible in multiplying machines, with a resultant higher operating speed of the machine as a whole.

65 In accordance with a modified form of the invention, the differential register may be of a somewhat modified form to permit the concurrent entry of left hand and right hand partial products therein so that in the single cycle of operation, a complete entry will be made of the true product obtained by the multiplication of the entire multiplicand by one of the digits of the multiplier. With this type of construction, the number of computing cycles will be exactly equal
70 to the number of digits in the multiplier factor.

Various other objects and advantages of the invention will be obvious from the following particular description of two forms of mechanism embodying the invention or from an inspection of the accompanying drawings; and the invention also constitutes certain new and novel features of construction and combination of parts hereinafter set forth and claimed.

In the drawings:

Figs. 1, 1a and 1b, placed side by side in the 10 order mentioned, comprise a complete circuit diagram of the preferred form of the invention.

Fig. 2 is an example of a multiplying computation as performed by the machine and illustrates the successive steps of operation of the machine 15 which are required to obtain a product.

Fig. 18 is a further detail of the driving mechanism of the modification. The machine comprises several separate sec-

Factor entry devices

In general, the machine may be stated to comprise factor entry sections, one for the multiplicand, and one for the multiplier. While the invention is not limited to the particular form of factor entry means herein shown, such factor entry means as here disclosed comprise a multi-columnar key type of entry means for the multiplicand and a single column of keys for the multiplier. In Fig. 1, the column of multiplier keys is generally designated MP and the bank of multiplicand keys in Fig. 1b is designated MC. Fig. 11 shows the details of the multiplicand keys 75

10, each of which has a conducting strip 11 secured to and insulated from its lower end, which, upon depression, is adapted to engage contact elements 12 arranged as shown. A latching plate 13 is provided, which is adapted to hold a selected key in depressed position in accordance with the usual manner of constructing keyboards.

The multiplier keys are similar in construction and are shown in diagrammatic form in Fig. 1. 10 They are designated 10a and each is adapted upon depression to close one or more contacts 12a as indicated. Nine such keys are provided, and for a complete multiplying operation it is necessary to depress four keys in succession. 15 The machine as arranged requires four multiplying cycles for each problem and if the multiplier has less than four digits, the zero key must be depressed a number of times necessary to bring about four multiplying cycles. The usual key 20 interlocks (not shown) may be provided to prevent depression of more than one key at a time. Latching plate 13a is provided to hold the keys depressed until the multiplying operations they control are completed when a magnet 11a is 25 energized to release the same and permit depression of the next key. The control for magnet 11a will be more fully explained hereinafter. It is therefore apparent that a multi digit multiplicand and a digit of a multiplier are separately 30 set up on their respective keyboards MP and MC to close the selected contacts 11, 12 and 12a and that the setting of the multiplicand keys will be maintained until they are released by moving the latching plates 13 either separately 35 or collectively.

For convenience of illustration, the multiplicand key bank has been limited to four columns and the machine will be described as a fixed cycle machine; that is, a definite predetermined 40 number of operating cycles will take place for each multiplying operation to be performed, although it is to be understood that the capacity of the device may be readily altered without departure from the spirit of the invention.

45

Multiplying commutators

The machine further comprises a multiplying commutator section which is shown in Fig. 1a and which comprises nine individual commutator 50 assemblies in which the commutators are stationary and internal brushes are provided to cooperate with the inner surfaces of the commutators. This multiplying commutator section takes the factors as derived from the keyboards and multiplies them and controls the accumulation of partial products into the accumulating means.

Referring to Figs. 13 and 14, each commutator 60 comprises a central common conducting ring 14, a lower or right hand emitting section 15, and an upper or left hand emitting section 16. A brush 17 carried by an arm 18 secured upon a shaft 19a is adapted to cooperate with the sections 14, 15 and 16 during the rotation of the shaft 19a.

Accumulator

The next general section of the machine 70 comprises the accumulator or register shown in Figs. 4 to 8 and in the upper left hand portion of Fig. 3. The accumulator includes in each denominational order the driving gear 20, which is secured to shaft 19 connected by a 2:1 gear ratio 75 to shaft 19a upon which the brushes 17 are

mounted. The gear 20 therefore makes two revolutions for each revolution of the commutator brushes 17. Adjacent to gear 20 is a gear 21 which is adapted to be coupled for driving engagement with gear 20 under control of a magnet 5 22. Energization of magnet 22 will attract its armature 23 and will permit clockwise rotation, as viewed in Figs. 5 and 6, of arm 24 which carries a pinion 25 at its upper end. Pinion 25 is adapted to engage gears 20 and 21 simultaneously so that the former drives the latter during the period that pinion 25 is in engagement therewith. Gear 20 carries a pin 26 which is adapted to strike an extension 27 on arm 24 to disengage the parts and restore arm 24 to its latched position. This restoring action takes place at the end of a cycle of shaft 19 and the angular displacement of the gear 21 will accordingly be dependent upon the time of energization of magnet 22. The operation of the accumulating 20 mechanism is in accordance with a ten point cycle so that if magnet 22 is energized six points before pin 26 strikes extension 27, an entry of six 25 will accordingly be made on the gear 21. Integral with gear 21 are internal teeth 28 meshing with a differential pinion 29 which is mounted upon differential gear 30. The differential gear 30 carries a second pinion 31 meshing with pinion 29 and also in engagement with an internal gear 32 Fig. 9. The gear 32 is also provided with 30 teeth on its outer circumference which are in engagement with carrying pinion 33 carried by a rod 34 which rod has a second carrying pinion 35 at its opposite end.

This second carrying pinion is adapted to co-operate with a mutilated gear 36 which is integral with the differential gear 30 of the next lower denominational order.

In accordance with the well known manner of operation of a differential entering device, if 40 gear 32 is restrained against rotation, turning of gears 21 and teeth 28 will drive the differential gear 30 a proportionate distance, in this case, one-half the angular distance, and likewise, if gear 28 is restrained against rotation, turning 45 of gear 32 will similarly advance the differential gear 30. Of course, both gears 32 and 28 may be turned at the same time in which case the differential gear 30 will be driven a distance proportional to the sum of the movement of the 50 gears 32 and 28.

In Fig. 6, a spring pressed arm 37 is provided which normally restrains gear 21 against rotation while the parts are in the position shown and which releases gear 21 when the latter is 55 being driven. In Fig. 7 the teeth on the gear 36 are so located that they drive the pinion 35 as the gears 30 and 36 pass through the zero position, thereby also turning gear 33 to advance the next higher denominational order 60 gear 32 a distance equivalent to the entry of one. By virtue of the arrangement of the accumulator just described, this carrying entry of one may be effected while an entry is being made into 65 the same order under control of the magnet 22. This arrangement makes it unnecessary to provide additional index points in the operating cycle of the machine to obtain time for performing carrying operations after each entry as has 70 heretofore been the practice, thus permitting shorter machine cycles and the consequent more rapid operation of the entire apparatus. A detenting pawl 37a engages gear 32 to hold the 75 same impositively.

Printing mechanism

As shown in Figs. 4 and 8, each differential gear 30 is adapted to drive a gear 40, each of which is connected to one end of one of a nest 5 of sleeves 41, which, at their opposite ends, carry printing wheels 42 above which any suitable record material 43 may be placed and upon which may be printed the result of the computation; namely, the product of the factors set up 10 on the keyboards MC and MP.

Provision is made in the form of a printing hammer 44 and an armature latch 45, which latch is adapted to release the hammer 44 upon energization of magnet 46. This energization is arranged to take place at the completion of the computation of the product so that an impression thereof may be taken upon such completion. Suitable means (not shown) may be provided for 20 relatching hammer 44.

Machine drive

Referring to Fig. 3, the motive power for operating the machine is provided by the motor M which drives a gear 47 loose upon shaft 19a and having integral therewith a clutch driving element 49 which is also shown in Fig. 10. Secured upon shaft 19a is a clutch disk 50 integral with a gear 51. The disk 50 carries the usual spring 30 pressed clutching pawl 52 held in the position shown in Fig. 10 by the latching armature 53 of a clutch magnet 54. This clutch device is of the usual one-revolution type and momentary energization of magnet 54 will release the pawl 52 for engagement with driving member 49 whereupon the shaft 19a and gear 51 will be driven for one complete revolution, the parts de-clutching automatically at the end of such revolution.

The machine is arranged to effect a complete multiplication of two four place factors during 40 four revolutions of shaft 19a and to effect the printing of the product at the end of the fourth revolution. Gear 51 is adapted to drive shaft 48 through an idler gear 55 and a gear 56 carried by shaft 48, the ratio being such that shaft 19 makes 45 four revolutions for one revolution of shaft 48.

Referring to Fig. 1, the motor M receives current immediately upon closure of switch S thus causing the driving element of the one revolution clutch to operate. Clutch magnet 54 has a pair 50 of contacts 57 in series therewith which is adapted to be closed upon depression of a bar 58.

Depression of any key 10a will close contacts 57 to complete the circuit through magnet 54 and shaft 19a will consequently make one revolution 55 during which the product of the multiplicand and the digit represented by the depressed key 10a will be entered in the accumulator in a manner to be described. Toward the end of this revolution of shaft 19a, a cam 59 carried thereby momentarily closes a pair of contacts 60 to energize latch releasing magnet 11a so that key 10a may be released. Depression of another key 10a will repeat the cycle of operations and if the key depression follows closely upon the action of latch 65 releasing magnet 11a the succeeding cycle of shaft 19a will continue without interruption, since under such conditions the timing of the parts will permit reclosure of contacts 57 and reenergization of magnet 54 before shaft 19a is 70 declutched.

Column shift mechanism

In Figs. 1a and 12 are shown a plurality of commutators 68 having cooperating brushes 69 and 75 collector rings 70. These commutators are simi-

lar in structure to the commutators 15 and 16 and their brushes are carried by the shaft 48. The function of the commutators 68 and brushes 69 is to allocate the partial products to the proper denominational orders of the accumulating device. 5

It will be noted that the commutators are all identical in structure, each having five separate conducting segments interconnected as shown in the circuit diagram. 10

General operation

Before tracing the detailed operation of the machine, a general explanation of the manner of assembling the partial products to produce the 15 product will be made in connection with Fig. 2. Here it is proposed to multiply 2697 by 3485.

It has been pointed out above that for a complete multiplying operation of two four-place factors shaft 48 will make one revolution, shaft 19a will make four revolutions and shaft 19 will make eight revolutions. 20

During the first two cycles of shaft 19, the multiplicand is separately multiplied by the units digit of the multiplier, that is, 5, and the resulting right hand partial product of 55 is entered into the units and tens orders of the accumulating device, the 5 in the units position being the right hand figure derived from the multiplication of 5 times 7 or 35 and the 5 in the tens position 30 being the right hand figure of the result of the multiplication of 5 times 9 or 45. 5 times 6 being 30, producing a right hand or units figure of zero will, of course, effect no significant entry; similarly, for the product of 5 times 2. These entries are made in the first cycle of shaft 19. During the second cycle, the left hand figures of the separate computations are entered into the accumulating device and the relationship of the circuits to the accumulator is varied so that the entries are made with the tens order receiving the lowest denominational order of this partial product. In the third and fourth cycles, the right and left hand partial products of the result of multiplying the multiplicand by 8, the tens digit of the 40 multiplier, are successively entered as indicated, the tens partial product being entered one position higher than the units. It will be understood that as these entries are successively made to the various orders of the accumulator, the carrying operations involved when the accumulator gears or wheels pass through zero or ten position 45 will be automatically effected. During the remaining cycles, the several partial products as indicated will be entered into the accumulating device in the denominational orders as represented in Fig. 2, so that at the completion of the eighth cycle of shaft 19 or the single revolution of shaft 48, the amount 9399045 will stand on the accumulating device and on the printing wheels 50 and the printing hammer will have been tripped to transfer this reading to the record material. 55

The accumulating device may be provided with resetting mechanism to restore the unit to zero position but for the sake of simplicity, this mechanism has been omitted from the drawings. If it is desired to reset the accumulating device without the incorporation of additional mechanism, such operation may be readily effected by manually turning the printing wheels 42 so that each 60 indicates zero. By virtue of their gear connection with the differential gears 30, the latter will be similarly displaced. 65

Circuit diagram

The detailed operation of the machine will now 70

be explained in connection with the circuit diagram in Figs. 1, 1a and 1b and in accordance with the problem of Fig. 2. The keys of the multiplicand keyboard MC will be set and latched to 5 represent the value 2697 and these keys will close their corresponding contact devices 11, 12. The machine is now ready to commence multiplying operations, switch S having previously been closed. The "5" key 10a, in accordance with the units 10 digit of the multiplier is then depressed and latched, closing contacts 57, which as explained above will initiate a revolution of shaft 19a and an accompanying two revolutions of shaft 19 and a quarter revolution of shaft 48. In the diagram, 15 groups of wires and segments are designated with a single reference numeral identifying the group and specific wires or segments are identified by the group number followed by a numeral; for example, 78-9 indicates the ninth wire of the 20 group of wires generally designated 78 and 15-5 indicates the "5" segment of the group generally designated 15.

Brushes 17 (Fig. 1a) will proceed to traverse the segments 15 of the multiplying commutators 25 and when the brush 17 of the "7" position commutator is at the "5" position segment 15, specifically 15-5, a circuit will be completed which may be traced as follows: From line 75 (Fig. 1), wire 76, wire 77 in the "5" multiplier key position, 30 lowermost contact 12a-5, wire 18-9 of a group of fourteen wires generally designated 18 (see also Fig. 1a), segment 15-5 of the "7" connector brushes 17, corresponding collector ring 14, wire 79-7 of a group of wires 79 (see also Fig. 1b), 35 contacts 11, 12 of the "7" key 10 in the units order of the multiplicand, wire 80-1 (Fig. 1a), collector ring 10 of the right hand commutator 68, brushes 69, segment 68a, wire 81, units order accumulator magnet 22, wire 82 (Fig. 1) to other 40 side of line 83.

This circuit has been shown in heavy lines to facilitate the tracing of its path. The completion of the circuit at the "5" time in the cycle of the accumulator will cause the entry of a "5" 45 in the units order of the accumulator.

A second circuit will be concurrently completed through a similarly traceable circuit to enter a "5" in the tens order magnet 22 as the result of the multiplication of 5 and the tens digit 50 "9" of the multiplicand. This circuit will be substantially the same as that traced, flowing along wire 78-9 (Fig. 1a) and branching to continue to segment 15-5 of the "9" multiplying commutator, thence to wire 79-9 (Fig. 1b), contacts 11, 12 of the "9" key in the tens order of the multiplicand wire 80-2 (Fig. 1a), commutator 55 68, segment to wire 84 and the tens order magnet 22.

Thus at the end of the first half revolution of 60 shaft 19a the amount 55 as indicated in the "first cycle" line of Fig. 2 will have been entered as indicated. During this cycle brushes 69 (Fig. 1a) traversed segments 68a and during the next half revolution of shaft 19a these brushes will traverse 65 part of segments 68b to provide the denominational order column shift as will be clear from the circuits to be presently traced.

During this following operation brushes 17 will 70 traverse the upper segments 16 and circuits will be completed in accordance with the right hand components of the multiplication of 5 and 2697. Taking, for example, 5 times 7, when brush 17 reaches the segment 16-3 of the "7" multiplying commutator the following circuit will become 75 effective: From line 75 (Fig. 1), wire 76, wire 77

in the "5" key position, closed contact 12a-3, wire 85, wire 86-1 of a group 86 (Fig. 1a), segment 16-3, brushes 17, collector ring 14, wire 79-7 (Fig. 1b), contacts 11, 12 of the "7" position in the units column of the multiplicand, wire 80-1 (Fig. 1a), collector ring 10, brushes 69, segment 68b, wire 84, tens order magnet 22, wire 82 to line 83 as before.

During this same half revolution of shaft 19a parallel circuits will cause entry of a "1", a "4" 10 and another "3" in other denominational orders of the accumulator in accordance with the "2nd cycle" line of Fig. 2, so that at the completion of a single revolution of shaft 19a the complete product of 5 and 2697 will be recorded.

With the "5" multiplier key 10a released at the end of the cycle and the key "8" thereafter depressed in accordance with the tens digit of the multiplier, the shaft 19a will enter upon a second revolution during the first half of which the 20 amount shown on the "3rd cycle" line of Fig. 2 will be entered and during the second half, the amount represented on the "4th cycle" line will be entered. Subsequent depression of the "4" multiplier key and then the "3" multiplier key will add 25 further amounts in the positions shown, commutators 68 controlling the selection of the denominational orders into which the various amounts are to be entered.

At the end of the last multiplying operation, 30 which is coincident with the completion of a full revolution of shaft 48, a cam 87 on this shaft will momentarily close contacts 88 to energize print magnet 46 to transfer the reading on the accumulator to an appropriate record. Resetting 35 may then be effected as outlined above. It will be noted that each key 10a (Fig. 1) closes a plurality of contacts 12a, some of which complete the LH partial products circuits and the others complete the RH partial products circuits; for example, the uppermost contacts of key 10a related to "5" complete the LH circuits for all computation of $5 \times 2, \times 4, \times 6, \times 7, \times 8$, and $\times 9$ while the second completes the LH circuits for 5×3 and 5×5 . The third contacts complete the RH circuits for 5×5 only and the lowermost completes the RH circuits for $5 \times 1, \times 3, \times 7$, and $\times 9$.

Modification

A modified form of the invention is shown in 50 Figs. 15 and 16 by means of which the partial products associated with each digit of the multiplier may be simultaneously entered into the receiving device. Each denominational order there- 55 of comprises a differential gear 100 having differential pinions 101 which are driven by gears 102 and 103 in the well known manner. Gear 103 is in engagement with a gear 104 driven from a gear 105 on shaft 19' through the medium of connecting pinion 106 which may be brought into action under the influence of magnet 107L in a manner already explained.

Gear 102 is in engagement with a gear 104a driven from a gear 105a on shaft 19'' through the medium of connecting pinion 106a which may be brought into action under the influence of magnet 107R. Gears 105 and 105a are driven from shaft 19'a in a two to one ratio, that is; the gears make one revolution for each half revolution of shaft 19'a.

A second differential gear 108 is provided for 70 each order with pinions 109 pivoted thereon, the former being driven by a gear 110 which meshes with differential gear 100 and the latter being driven by a gear 111. Gear 111 is driven 75

through pinions 112 from mutilated gear 113 of the next lower order for carrying purposes in exactly the same manner as gear 32 of the preferred form.

- 5 It therefore becomes evident that with the construction just described, two entries may be concurrently made on gear 100 and the combined result impressed upon gear 110 to be further transferred to gear 108. Digits to be carried 10 are concurrently entered on gear 108 so that the latter gears ultimately represent the product of the multiplication performed. Printing of the product may be effected as in the preferred form through gears 114 and type wheels 115.
- 15 Figs. 1, 17 and 17a placed side by side with Fig. 1 on the left and Fig. 17a on the right, comprise a complete circuit diagram of the modified form of the device which will now be described. The same problem is chosen for purposes of explanation as was used in explaining the preferred form and the same procedure in setting up the successive digits of the multiplier is followed. Each key of the multiplicand keyboard is provided with two contact devices 11', 20 12', and 11'', 12'', the former for controlling the left hand partial product circuits and the latter for the right hand partial product circuits. The contacts are separately grouped in Fig. 17a to avoid complications in the wiring arrangement 25 30 and to render the separate circuits more readily traceable.

The multiplying commutators (Fig. 17) are provided with double brushes 17' and 17a and the corresponding collector ring is comprised of 35 two separate strips 14' and 17a. This arrangement permits both upper and lower groups of segments of the multiplying commutator to be read during a half revolution of the brushes. In Fig. 18 is shown the modified gearing arrangement between the various elements. Shaft 19'a upon which the multiplying commutators are mounted is driven from clutch element 49' under control of a half revolution clutch controlled by magnet 54' which is controlled identically as 40 magnet 54 in the preferred form. It follows then, that four half revolutions of shaft 19'a will be enough to take care of a four place multiplier. Since shaft 48' which carries the column shift 45 commutators is to make but a single revolution for a complete problem it is geared as shown with a two to one drive from shaft 19'a. Shafts 19' and 19'' of the accumulator are geared to make 50 a complete revolution for a half revolution of shaft 19'a.

- 55 Returning now to Figs. 1, 17 and 17a, the operations involved in the multiplication of the multiplicand by the first or units digit of the multiplier will now be traced from which the steps involved in the remaining cycles will be 60 apparent. With the multiplicand 2697 set up on the keyboard, depression of the "5" multiplier key will energize magnet 54' to initiate the first half revolution of shaft 19'a.

As brush 17a (Fig. 17) contacts segment 15'-5 65 a circuit may be traced as follows: From line 75 (Fig. 1), wire 76, wire 77, contact 12a-5, wire 78-9, (Fig. 17) segment 15'-5, brush 17a, collector strip 14a, wire 79a-7 of group of wires 79a (Fig. 17a), contacts 11'', 12'' in the "7" position of the units order of the multiplicand, wire 80a-1, collector ring 70a, brush 69a, segment 70

68'', wire 81a to the units order accumulator magnet 107R, wire 82, back to line 83. This will cause the entry of a "5" in the units order of the accumulator.

During the same half revolution, when brush 17' (Fig. 17) contacts segment 16'-3, a parallel circuit may be traced as follows: From line 75 (Fig. 1), wire 76, wire 77, contact 12a-3, wire 86-1 (Fig. 17), segment 16'-3, brush 17', collector strip 14', wire 79'-7 of a group of wires 10 79' (Fig. 17a), contacts 11', 12' in the "7" position of the units order of the multiplicand wire 80'-1, collector ring 70', brush 69', segment 68', wire 81', to tens order accumulator magnet 107L, wire 82, to line 83.

Also, during this same half revolution, parallel circuits will be completed through the other order of the multiplicand keys to enter a "5" in the tens order magnet 107R and "1", "3" and "4" in the ten thousands, thousands, and hundreds 20 order magnets 107L, so that at the completion of the half revolution, the complete product of "5" and "2697"; namely, 13485, will have been entered into the single accumulator.

Depression at this time of the key of the 25 multiplier representing the tens digit of the multiplier will be followed by appropriate column shifting and entry of the product of "8" and 2697 into the accumulator.

While there has been shown and described 30 and pointed out the fundamental novel features of the invention as applied to two modifications, it will be understood that various omissions and substitutions and changes in the form and details of the devices illustrated and in their operation may be made by those skilled in the art 35 without departing from the spirit of the invention. It is the intention therefore to be limited only as indicated by the scope of the following 40 claim.

What is claimed is:

In a multiplying machine, a plurality of multiplying commutator devices, one for each of the digits of a notation and each being arranged to emit impulses representative of the product of 45 one of said digits times all the digits, a plurality of multiplicand keys settable to represent a multidenominational multiplicand, a digit line connecting each digit representing commutator device to the keys corresponding to the same digit, 50 a plurality of multiplier keys, one for each significant digit, a set of pairs of contacts for each multiplier key, a set of eight digit representing lines connecting said commutator devices to one, two or three pairs of contacts of each key, a 55 second set of fourteen digit representing lines connecting said commutator devices to one, two or three other pairs of contacts of each key, the maximum number of pairs of contacts in any set being six, and means controlled upon operation of any multiplier key for effecting an operation of said commutator devices to complete a circuit through one of the pairs of contacts, the set of eight lines and the first named set of lines in accordance with the left hand partial products 60 and a circuit through another of the pairs of contacts, the set of fourteen lines and the first named set of lines in accordance with the right hand partial products of the multiplier digit and the amount set on the multiplicand keys. 65
